UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

ROCK DRILL.

Application filed June 2, 1927. Serial No. 196,110.

This invention pertains to rock drills and more particularly to a hole blowing device for a fluid actuated rock drill of the hammer type.

5 An object of this invention is to provide an improved rock drill hole blowing device. Another object is to provide an improved hole blowing device for a fluid actuated rock drill of the hammer type whereby the fluid 10 distribution valve controlling the supply and exhaust of pressure fluid to the drilling motor is held immovable to effect a hole blowing operation. A further object of this invention is to provide an improved hole blowing 15 device including means whereby the resisting throwing pressure at one end of the fluid distribution valve is vented to atmosphere, thereby permitting the valve to be manually shifted and held immovable with facility. These 20 and other objects and advantages of this invention will, however, more fully appear.

In the accompanying drawing I have shown for purposes of illustration one form which the invention may assume in practice.

25 In this drawing,—

Fig. 1 is a central, longitudinally extending, vertical sectional view taken through a rock drill embodying the improved hole blowing device, the parts being shown in position 30 to effect a hole blowing operation.

Fig. 2 is a fragmentary sectional view similar to that shown in Fig. 1 with the parts shown in a different position.

In this illustrative construction there is 35 shown a rock drill of the fluid actuated hammer type comprising a cylinder 1 having a bore 2 in which is reciprocably mounted a hammer piston 3. The piston 3 is provided with a forwardly projecting striking bar 4 extending through a bore 5 formed within a 40 usual front cylinder head 6. The striking bar 4 is adapted to impart a series of blows to the shank of a hollow drill steel 7 herein of hexagonal cross section. The drill steel 7 is loosely mounted in a usual manner within a 45 hexagonal opening formed in a chuck bushing 8 secured to a chuck sleeve 9 rotatably mounted within a usual chuck housing 10. As illustrated, the rear end of the cylinder 50 bore 2 is closed by a washer 11 while interposed between this washer and a rear head member 12 is a usual ratchet ring 13 to be later referred to. The chuck housing 10, the front cylinder head 6, cylinder 1, rear washer 55 11, rear head 12, and the ratchet ring 13 are

held in assembled relation in any suitable and convenient manner, for instance by usual side rods or bolts (not shown).

The cylinder 1 has preferably formed integral therewith a valve chest 14 having a bore 15 herein arranged parallel with the cylinder bore. Disposed within the bore 15 are oppositely positioned sleeves 16 and 17 each having an enlarged central bore 18 and a reduced outer bore 19. As shown in Fig. 1 60 the sleeve 16 has suitably secured thereto a valve buffer plug 20 while secured to the sleeve 17 is a buffer plug 21 held in position by a suitable nut member 22. Reciprocably mounted within the bores 18 and 19 formed in the sleeves 16 and 17 is an automatic fluid 65 distribution valve 23 herein of the well known three spool differential type having reduced end spools 24 and an enlarged central spool 25, the central spool being mounted in the bores 18 while the end spools are mounted in the bores 19. Reciprocable movement of the valve 23 in opposite directions is limited by the buffer plugs 20 and 21. The central spool 25 of the valve shown controls a central inlet port 26 while the end spools 24 respectively control usual exhaust ports 27 and 28 formed at the opposite sides of the inlet port 26 and leading directly to atmosphere. Motive fluid for actuating the piston 3 is supplied and exhausted from the rear and front 75 ends of the cylinder bore 2 through combined supply and exhaust passages 29 and 30 respectively communicating with the valve chamber on opposite sides of the central inlet 80 26. The action of the distribution valve 23 is controlled by usual crossed throwing passages 31 and 32, the former connecting the front end of the cylinder bore with the bore at the rear end of the valve, while the 85 throwing passage 32 connects the rear end of the cylinder bore with a bore at the front end of the valve. These throwing passages are controlled by the piston 3 and are employed for alternatively admitting pressure fluid 90 from the cylinder bore to the opposite ends of the distribution valve to effect reciprocation thereof, the pressure fluid admitted to the passage 31 throwing the distribution valve forwardly while the pressure fluid admitted to the passage 32 throws the valve rearwardly all in a well known manner.

The hollow drill steel 7 is adapted to be intermittently rotated during reciprocation of the hammer piston and this is accomplished 100 105 110

by a usual ratchet and pawl mechanism including a rotatable pawl carrier 33 carrying usual spring pressed pawls which cooperate with internal ratchet teeth 34 formed within the ratchet ring 13. Herein preferably formed integral with this pawl carrier and projecting forwardly through the washer 11 and within the rear end of the cylinder bore is a rifle bar 35 having spiral grooves 36 on its periphery. The spiral grooves 36 cooperate with spiral keys 37 carried by a rifle nut 38 threadedly connected within the rear end of the hammer piston 3. As shown, the striking bar 4 of the piston has formed on its periphery straight longitudinally extending grooves 39 which cooperate with straight keys 40 carried by a chuck nut 41 threadedly connected to the chuck sleeve 9. During forward movement of the hammer piston 3 the pawls of the pawl carrier slip over the teeth on the ratchet ring 13 and consequently the hammer piston delivers an unimpeded blow to the shank of the drill steel 7. Upon the return stroke of the hammer piston the pawls engage the ratchet teeth 34 thereby positively preventing rotation of the rifle bar and consequently during this return stroke of the piston the latter is slightly rotated. Rotation of the piston is transmitted through the straight grooves 39 on the striking bar, straight keys 40 on the chuck nut, the sleeve 9 and the chuck bushing 8 and consequently the drill steel is rotated. The construction described above is usual in rock drills of the type disclosed and further description of the same is herein considered unnecessary.

The improved hole blowing device comprises a reciprocable plunger valve 42 arranged coaxially with the distribution valve 23 and slidably mounted within a central bore 43 in the valve and bores 44 and 45 formed in the buffer plugs 20 and 21 respectively. The portion of the valve 42 extending through the bore 43 in the distribution valve and the bore 44 in the buffer plug 20 is reduced, thereby leaving a shoulder or abutment 46 adapted to engage the forward end surface of the distribution valve as hereinafter described. The plunger valve 42 is externally grooved at 47 at its rearward end and is provided at its forward end with a conveniently located push button 48. As shown, the buffer plug 20 has formed therein radial ports 49 connecting the bore 44 with the bore 19 at the rear end of the distribution valve 23, while also formed in this buffer plug and the valve sleeve 16 are radial ports 50 which connect the bore 44 with the atmosphere. In this instance, the plunger valve 42 is held in its released or inoperative position as shown in Fig. 2 by means of a coiled spring 51 seated within a bore 52 formed in the buffer plug 21 and engaging a transverse pin 53 carried by the valve 42. The plunger valve 42 has formed centrally therein restricted vent passages 54

and 55, which are adapted to connect the bores at the ends of the distribution valve 23 to atmosphere when the plunger valve 42 is in its released position.

In the normal operation of the rock drill pressure fluid flows through the central inlet passage 26 and when the valve is in the position shown in Fig. 2 fluid flows past the rear surface of the central spool 25 of the distribution valve 23 and through the passage 29 to the rear end of the cylinder bore 2 where it acts on the rear surface of the piston 3 and moves the latter forwardly to strike a blow on the drill steel 7. The exhaust from the front end of the cylinder bore 2 flows out through the passage 30 past the rear surface of the forward spool 24 and through the exhaust passage 28 to atmosphere. The distribution valve 23 is held in its forward position against the front buffer plug 21 by reason of the larger effective area of the central spool 25. When the piston 3 uncovers the throwing passage 32 pressure fluid is admitted from the cylinder bore to the forward end of the distribution valve 23 and consequently the latter is thrown rearwardly against the rear buffer plug 20 as shown in Fig. 1. Pressure fluid now enters the forward end of the cylinder bore through inlet passage 26 past the forward surface of the central spool on the distribution valve and through passage 30 and consequently the hammer piston is moved rearwardly. The exhaust now takes place through passage 29 past the forward surface of the rear spool 24 and through the exhaust passage 27 to atmosphere. The plunger valve 42 is in its released or inoperative position at this time as shown in Fig. 2 and the restricted vent ports 54, 55 therein prevent any back pressure from building up in the bores at the ends of the valve and as a result the valve action is materially quickened. As soon as the piston 3 has uncovered the throwing passage 31 the distribution valve 23 is again shifted to its forward position and this cycle continues throughout the normal operation of the drill.

When it is desired to effect a hole cleansing operation, the operator presses against the push button 48 and moves the plunger valve 42 rearwardly from the position shown in Fig. 2 until the groove 47 connects the ports 49 and 50 and consequently the pressure fluid in the bore at the rear end of the distribution valve 23 tending to throw the latter forwardly is vented to atmosphere. Upon further rearward movement of the plunger valve 42 the shoulder 46 directly engages the forward end surface of the distribution valve, thereby permitting the latter to be manually shifted with facility against the relatively small opposing pressure acting on the central spool 25. When the distribution valve 23 is held in its retracted position as shown in Fig. 1, pressure fluid flows from the inlet 26 past the for-

ward surface of the central spool 25 of the distribution valve and through the passage 30 to the forward end of the cylinder bore. The continuous pressure flowing to this end of the cylinder bore forces the hammer piston 3 rearwardly against the rear cylinder washer 11 and consequently pressure fluid then flows from the cylinder bore through the flutes 39 on the striking bar 4, through the chuck nut 41, and thence through the bore in the drill steel 7 to the bottom of the drill hole. As soon as the manual pressure on the push button 48 is released, the plunger valve 42 is automatically returned to its inoperative position by the spring 51 and the distribution valve 23 then resumes its normal operation and the drill will again function in a normal manner.

As a result of this invention it will be noted that an improved hole blowing device is provided whereby the distribution valve can be actuated and held without material resistance and without the necessity of manually shifting the valve against the relatively great resisting throwing pressure. It will further be noted that by venting the space at the rear end of the valve to atmosphere it is possible to manually shift the distribution valve rearwardly with facility, it being only necessary to move the valve against the relatively small opposing pressure acting on the central spool of the valve. These and other advantages of this invention will be clearly apparent to those skilled in this art.

While I have in this application specifically described one form which my invention may assume in practice, it will be understood that this form has been shown for purposes of illustration and that the invention may be modified and embodied in various other forms without departing from its spirit or the scope of the appended claims.

What I claim as new and desire to secure by Letters Patent is:

1. In a fluid actuated rock drill of the hammer type, the combination of a cylinder and a piston reciprocable therein, a valve chest and a fluid distributing valve therein controlling both the supply and exhaust of pressure fluid for said cylinder, valve throwing passages between opposed spaces in the valve chest and the cylinder bore for supplying pressure fluid for actuating said valve, and a hole blowing device including means for venting the space at one end of the valve to atmosphere during a hole blowing operation and for directly engaging said valve to shift it toward said end and hold the same immovable.

2. In a fluid actuated rock drill of the hammer type, the combination of a cylinder and a piston reciprocable therein, a valve chest and a fluid distributing valve therein controlling both the supply and exhaust of pressure fluid for said cylinder, valve throwing passages between opposed spaces in the valve chest and

the cylinder bore for supplying pressure fluid for actuating said valve, and a hole blowing device including means for venting the space at one end of the valve to atmosphere, said means including an element extending 70 through said valve and manually operable from the opposite end of the valve and said element having an abutment portion for directly engaging the valve to hold the same immovable.

3. In a fluid actuated rock drill of the hammer type, the combination of a cylinder and a piston reciprocable therein, a valve chest and a fluid distributing valve therein controlling both the supply and exhaust of pressure fluid 80 for said cylinder, valve throwing passages between opposed spaces in the valve chest and the cylinder bore for supplying pressure fluid for actuating said valve, and means including an auxiliary valve for venting the space at 85 one end of said distributing valve to atmosphere and including means for directly engaging said distribution valve to shift it into said space and hold the same immovable whereby said piston is held at the rearward 90 end of its stroke to effect a hole blowing operation.

4. In a fluid actuated rock drill of the hammer type, the combination of a cylinder and a piston reciprocable therein, a valve 95 chest and a fluid distributing valve therein controlling both the supply and exhaust of pressure fluid for said cylinder, valve throwing 100 passages between opposed spaces in the valve chest and the cylinder bore for supplying pressure fluid for controlling said valve, and means including a plurality of ports for one of said valve chest spaces, one of said ports leading directly to atmosphere, and an auxiliary valve for connecting said ports for venting the space at rear end of said valve to atmosphere, and means movable with said auxiliary valve for directly engaging the distributing valve to shift it toward the rear end and hold the same immovable whereby 105 said piston is held at the rearward end of its stroke to effect a hole blowing operation.

5. In a fluid actuated rock drill of the hammer type, the combination of a cylinder and a piston reciprocable therein, a valve chest 110 and a fluid distributing valve therein controlling both the supply and exhaust of pressure fluid for said cylinder, valve throwing 115 passages between opposed spaces in the valve chest and the cylinder bore for supplying pressure fluid for actuating said valve, and a hole blowing device including means arranged coaxially with said fluid distributing valve for venting one of said valve chest spaces at one end of said valve to atmosphere 120 and for directly engaging the valve to shift it toward said end and hold the same immovable.

6. In a fluid actuated rock drill of the hammer type, the combination of a cylinder and 125

a piston reciprocable therein, a valve chest and a fluid distributing valve therein controlling both the supply and exhaust of pressure fluid for said cylinder, valve throwing 5 passages between opposed spaces in the valve chest and the cylinder bore for supplying pressure fluid for actuating said valve, manually operable means for venting the valve chest space at one end of said valve to atmosphere and for directly engaging said valve to shift and hold the same immovable to effect a hole blowing operation, and means 10 associated with said latter means for venting said valve chest spaces to atmosphere during 15 normal operation of said valve.

7. In a fluid actuated rock drill of the hammer type, the combination of a cylinder and a piston reciprocable therein, a valve chest and a fluid distributing valve therein 20 controlling both the supply and exhaust of pressure fluid for said cylinder, valve throwing passages between opposed spaces in the valve chest and the cylinder bore for supplying pressure fluid for actuating said valve, 25 means including an auxiliary valve for venting the valve chest space at one end of said valve to atmosphere and for directly engaging said distributing valve to shift and hold the same immovable to effect a hole blowing 30 operation, and means associated with said auxiliary valve for venting said valve chest spaces to atmosphere during normal operation of said fluid distributing valve.

8. In a fluid actuated rock drill of the hammer type, the combination of a cylinder and 35 a piston reciprocable therein, a valve chest and a fluid distributing valve therein controlling both the supply and exhaust of pressure fluid for said cylinder, valve throwing 40 passages between opposed spaces in the valve chest and the cylinder bore for supplying pressure fluid for actuating said valve, and

a hole blowing device including an auxiliary valve manually operable from the forward end of said distributing valve and arranged 45 coaxially therewith and extending therethrough for venting the valve chest space at the rear end of said valve to atmosphere during a hole blowing operation and for directly engaging said distributing valve to shift and 50 hold the same immovable to effect a hole blowing operation.

9. In a fluid actuated rock drill of the hammer type, the combination of a cylinder and a piston reciprocable therein, fluid distribution means for effecting reciprocation of said piston including a fluid distribution valve, and a hole blowing device comprising means including an element directly engaging said valve for mechanically shifting and holding 60 the same in one position and means controlled by a movement of said mechanical means for relieving the pressure tending to oppose shifting of the valve to the hole blowing 65 position.

10. In a fluid actuated rock drill of the hammer type, the combination of a cylinder and a piston reciprocable therein, fluid distribution means including a fluid actuated reciprocable valve, valve throwing passages 70 between opposed spaces in the valve chest and the cylinder bore for supplying pressure fluid for actuating said valve, and a hole blowing device comprising manually operated means for engaging and mechanically moving and 75 holding said valve in position to effect a hole blowing operation and valve means automatically operative on movement of said manual means prior to shifting of the valve to vent the pressure fluid in said space tending to oppose shifting of said valve to atmosphere.

In testimony whereof I affix my signature.

CHARLES F. OSGOOD.
